DESIGN FOR A PICTURE FRAME

Louis Mandel, Newark, N. J.

Application April 17, 1946, Serial No. 128,681

Term of patent 14 years

(Cl. D29—20)

To all whom it may concern:

Be it known that I, Louis Mandel, a citizen of the United States, residing in Newark, county of Essex, and State of New Jersey, have invented a new, original, and ornamental Design for a Picture Frame, of which the following is a specification, reference being had to the accompanying drawing, forming part thereof.

In the drawing:

I claim:

The ornamental design for a picture frame, as shown.

LOUIS MANDEL.
